UNITED STATES PATENT OFFICE.

JAMES H. BROWN, OF BUTTE, MONTANA.

ACETYLENE-GAS GENERATOR.

Application filed October 16, 1924. Serial No. 744,032.

To all whom it may concern:

Be it known that I, JAMES H. BROWN, a citizen of the United States, and a resident of Butte, in the county of Silverbow and State of Montana, have invented certain new and useful Improvements in Acetylene-Gas Generators, of which the following is a specification.

My present invention relates to acetylene gas generators and more especially to high pressure devices for the generation of acetylene gas, my primary object being the provision of an improved high pressure generator which may at the same time maintain a constant uniform output of gas, as well as a generator which will be entirely safe in operation and will remain cool at all times.

Generally speaking my invention proposes a generator in which carbide and gas collecting cylinders are depressed within a water chamber formed within the casing of the generator and within an inner cylinder of the casing so arranged as to form an air chamber above a portion of the water chamber. The air pressure within said air chamber opposes the pressure within the collecting cylinder in such manner that the water can only come up into the collecting cylinder when pressure in the latter falls to a predetermined point, and it is only when the water does come up into the collecting cylinder that it reaches the carbide in the carbide holder so that gas will be generated. The gas generated rises within the collecting cylinder and escapes from the collecting cylinder into a gas storage chamber, through a controlling valve which insures a steady relief of gas pressure from the collecting cylinder and thus when pressure accumulates in said cylinder it forces the water to recede from the carbide holder and against the pressure within the air chamber which latter pressure again forces the water up to the carbide holder when pressure within the receiving chamber is again lowered by virtue of the escape of gas therefrom through said valve.

In the accompanying drawings, illustrating my present invention and forming a part of this specification,

Figure 1 is a central vertical section through my improved generator,

Figure 2 is a similar view taken at right

angles to Figure 1 on the line 2—2 of said figure,

Figure 3 is a top plan view, and

Figure 4 is a cross section taken on line 4—4 of Figure 1.

Referring now to these figures my improved generator includes a vertical cylindrical casing 10 having an upper reduced cylindrical portion 11 with an annular offset 12 between these portions, the top of the upper reduced portion 11 being open and being closed in the operation of the generator by means of a flat closure plate 13 held in place by a clamp 14 hingedly mounted at one end as at 15 to one side of the said open top and engaged at its opposite side by a clamping screw 16 working on a pivoted threaded bolt 17. This clamp 14 has its opposite side portions provided with depending extensions 18 which engage the top of the plate 13 in the operative position of the parts.

The casing 10, which may have side handles 19 as seen in Figure 2 for its convenient transportation from place to place, forms within the lower portion thereof a water chamber 20 and has at the lower portion of said chamber a sloping bottom 21 and a cleanout opening and plug 22 at the lower portion of said sloping bottom.

Within the casing and rigidly fixed in place is an inner casing cylinder 23 whose body has an enlarged upper cylindrical portion 24 secured at its top to the offset 12 of the casing and also has a flaringly enlarged lower skirt portion 25, the lower outer edge of which extends into engagement with the inner surface of the casing 10 at a point spaced from the sloping bottom 21 and is recessed around said edge as at 26 so that the water chamber thus includes the lower portion of the inner cylinder 23 as well as the lower portion of the casing around said cylinder, up to the filling neck 27 projecting from the side of the casing as in Figure 1.

Diametrically across the lower surface of the lower skirt portion 25 of the inner casing cylinder 23 is a supporting strip 28 having a central upwardly offset portion 29, the latter forming a rest for the lower screened end 30 of a cylindrical carbide holder 31 adapted to contain carbide in the form of cakes 32, the lower portion of the

carbide holder having diametrically outstanding lugs 33.

Around the carbide holder a gas collecting cylinder 34 is disposed, with its lower end engaging the supporting strip 28 and with its wall spaced from the wall of the carbide holder to permit of the upward passage of generated gas to the gas collecting chamber 35 of said cylinder. The wall of the cylinder 34 is likewise spaced from the body 23 of the inner casing cylinder and the water extending up into this cylinder is prevented from passage upwardly into the collecting cylinder 34 except to the slight extent shown by virtue of the fact that the upper end of the gas collecting cylinder is closed and the entrapped air, as well as gas after the start of operations controls the surface of the fluid in the lowermost portion of the collecting cylinder maintaining the same below the lower end of the carbide holder 31 except when such pressure falls below a predetermined point.

25 The gas escapes through a controlling valve 36 at the upper end of the collecting cylinder 34 into the upper reduced portion 11 of the casing 10 which forms, in connection with the upper enlarged portion 24 of the inner casing cylinder above the level of fluid, a gas storage chamber 37. When gas escaping through the controlling valve 36 into the storage chamber 37 lowers pressure within the gas collecting chamber 35 below a predetermined point, the level of fluid in the lower portion of the gas collecting cylinder 34 rises to the carbide cakes 32 within the carbide holder 31, this rise of fluid being occasioned 40 by pressure within the pressure chamber 38 formed within the upper portion of the casing 10 above the level of fluid therein and between its wall and the upper enlarged portion 24 of the inner casing cylinder, predetermined pressure being introduced into this chamber through either a supply valve 39 shown in Figure 1 or through pressure control valve 39^a which as seen in Figure 2 connects chamber 38 with the gas storage 45 chamber 37. Through this communication there is allowed an interchange of pressures wherein the weight of water as at 20 under pressure chamber 38 acts in opposition to pressure in storage chamber 37, which in turn allows pressure in chamber 38 to build up to any point desired. By the closing of this valve 39^a, pressure ceases to raise and is held permanently in chamber 38; thus, by this interchange of pressures, pressure may be raised from atmospheric pressure to any desired point, without outside assistance. Pressure within chamber 38 acts in opposition to the pressure within the gas collecting cylinder 34 and it is 65 obvious that by utilizing gas through the

valve 39^a instead of air, I avoid the danger of an explosion, which often results from the mixture of air and acetylene gas at certain temperatures.

The gas collecting cylinder 34 has upper 70 internal guides 40 which engage the upper portion of the carbide holder in order to space the same uniformly within the cylinder. It is also provided adjacent to its lower end with internal spring catch members 41 engageable by the lugs 33 of the carbide holder so as not only to properly space the lower portion of the carbide holder within the cylinder but also prevent vertical movement of the carbide holder independent of the gas collecting cylinder. The gas collecting cylinder is in turn held in properly spaced relation within the inner casing cylinder 23 by virtue of the engagement of its lower end with the central seat portion 29 of the cross strip 28 and is further engaged at its upper portion by internal guide members 42 extending inwardly from the lower end of the upper 80 reduced portion 11 of the casing. Communicating with the upper reduced portion 11 of the casing and thus with the gas storage chamber 37 is a safety valve 43 and also attached thereto is a pressure gauge 44, the latter disposed diametrically opposite to a flash back chamber 45 into which below the level of water thereof opens the outer end of a gas outlet pipe 46 whose inner end opens into the gas storage chamber 37 and intermediate whose ends is a check valve 47. The flash back chamber has a filling neck and plug 48 and a lower cleanout opening and plug 49 and is also provided with an upper gas outlet valve 50 communicating therewith above the level of fluid therein. Thus the gas in storage chamber 37 outlets past the check valve 47 and below the surface of the water within the flash back chamber 45.

100 The closure plate 13 seats upon an inner annular rim 51 at the upper end of the reduced portion 11 of the casing and opening upwardly through this rim and normally closed by the cover plate 13 is the upper end of an air pipe 52 whose lower end opens into the air pressure chamber 38 before-mentioned, closure plate 13 being provided with a central stuffing box 53 upwardly through which the stem 54 of the controlling valve 36 is mounted. This stem 54 has an angular upper external portion provided with a downturned extremity 55, the latter disposed above a curved rib 56 of the clamp 14 when the valve is in open position, said rib being cut away at one end as plainly indicated in Figure 3 so as to thus force movement of the upper angular portion of the valve stem to closed position of the valve before the clamp 14 can be raised to release and permit removal of the top closure 110 115 120 125 130

plate 13. When the upper angular portion of valve stem 54 is turned to align with the cutaway end of the rib 56 it is obvious that upon removal of the nut 16, the clamp 14 5 may be raised and the top closure plate 13 will thus be loosened so that pressure within the air pressure chamber 38 is instantly relieved through the pipe 52. By grasping the upper angular end of the valve stem 54 10 the top closure plate 13, gas collecting cylinder 34 and the carbide holder 31 may be simultaneously removed in order that the carbide holder may be replenished and upon replacement of these parts it is obvious that 15 the top closure plate may be readily and easily clamped in proper position after which the desired air pressure is introduced into chamber 38 through the valve 39, or is gradually raised through the control 20 valve 39^a as previously described.

It is thus obvious that in operation there will be intermittent periods of generation of gas according to the rise and fall of pressure within the collecting chamber 35, the 25 level of fluid therein rising to the carbide by the pressure within the pressure chamber 38, and with the water being forced to recede below and away from the carbide as soon as gas collects in sufficient quantity and 30 pressure within the chamber 35 to overcome the pressure within the chamber 38.

The generator may thus be very properly termed a balanced pressure generator and can be readily operated at any desired pressure from atmospheric up to fifteen pounds 35 per square inch, the maximum allowable working pressure for free acetylene gas. The generator is extremely simple, durable, efficient in operation and inexpensive to 40 manufacture and is singularly devoid of all mechanical parts such as weight motors, clock motors, gas motors, diaphragms, and other moving parts, generally relied upon in acetylene generators, and which experience 45 has shown are in every instance attended by a fluctuation of pressures at the point of delivery and are susceptible of ready breakage, early deterioration and generally inaccurate.

50 It is to be understood, of course that various details of the structure as just described may be varied or modified, and that I reserve all such as fall within the spirit of my invention and within the terms of the 55 following claims.

I claim:

1. An acetylene gas generator including 60 a casing forming in the lower portion thereof a water chamber, an inner casing cylinder within the said casing forming with the latter a pressure chamber above the surface of the fluid therein and having a lower flared end connected to the casing and spaced above the base thereof, the flared portion being recessed to permit the fluid to pass into as well

as around the said inner cylinder, said inner cylinder forming with its upper portion and the upper portion of the casing a gas storage chamber having an outlet, a gas collecting cylinder opening downwardly within 70 the casing and into the fluid thereof, said cylinder being within and in spaced relation to the said inner casing cylinder and having a valved outlet at its upper end opening into the gas storage chamber, and a carbide 75 holder fixed within the lower portion of the said collecting cylinder and removable with the latter through the top of the casing and toward and away from which the surface of the fluid within the collecting cylinder is 80 shiftable under control of the opposing pressures within the collecting cylinder and the said pressure chamber.

2. An acetylene gas generator including a casing, a cylinder within the casing attached 85 at its upper and lower ends thereto and in communication at its lower portion with the casing, a downwardly opening gas collecting cylinder within and spaced from said first mentioned cylinder, a supporting cross 90 member upon which the lower end of said collecting cylinder rests, a carbide holder opening downwardly within and spaced from the gas collecting cylinder and supported by the latter for movement into and 95 out of the casing with the said collecting cylinder, said casing having a lower water chamber and a pressure chamber above the water chamber, means whereby to introduce 100 pressure within said pressure chamber, said inner cylinder forming within its upper portion and the upper portion of the casing a gas storage chamber having an outlet, a valved outlet at the upper portion of the said collecting cylinder opening into the 105 said gas storage chamber, and a controlling stem for the valve of the cylinder outlet, projecting exteriorly through a cap closing the upper end of the casing.

3. An acetylene gas generator including a 110 casing, a cylinder within the casing attached at its upper and lower ends thereto and in communication at its lower portion with the casing, a downwardly opening gas collecting cylinder within and spaced from said first mentioned cylinder, a supporting cross 115 member upon which the lower end of said collecting cylinder rests, a carbide holder opening downwardly within and spaced from the gas collecting cylinder and supported by the latter for movement into and out of the casing with the said collecting cylinder, said casing having a lower water chamber and a pressure chamber above the water chamber, means whereby to introduce 120 pressure within said pressure chamber, said inner cylinder forming within its upper portion and the upper portion of the casing a gas storage chamber having an outlet, a valved outlet at the upper portion 125 of the said collecting cylinder opening into the said gas storage chamber, and a controlling stem for the valve of the cylinder outlet, projecting exteriorly through a cap closing the upper end of the casing.

tion of the said collecting cylinder opening into the said gas storage chamber, a cap normally clamped upon the upper open end of the casing, having a central stuffing box, and a stem projecting upwardly from the outlet valve of the collecting cylinder and extending through said stuffing box.

4. An acetylene gas generator including a casing, a cylinder within the casing attached at its upper and lower ends thereto and in communication at its lower portion with the casing, a downwardly opening gas collecting cylinder within and spaced from said first mentioned cylinder, a supporting cross member upon which the lower end of said collecting cylinder rests, a carbide holder opening downwardly within and spaced from the gas collecting cylinder and supported by the latter for movement into and out of the casing with the said collecting cylinder, said casing having a lower water chamber and a pressure chamber above the water chamber, means whereby to introduce pressure within said pressure chamber, said inner cylinder forming within its upper portion and the upper portion of the casing a gas storage chamber having an outlet, a valved outlet at the upper portion of the said collecting cylinder opening into the said gas storage chamber, a cap normally clamped upon the upper open end of the casing, having a central stuffing box, a stem projecting upwardly from the outlet valve of the collecting cylinder and extending through said stuffing box, and a clamp for securing the cover in place having means cooperating with the valve stem to prevent removal of the clamp except when the valve has been shifted to closed position.

40. 5. An acetylene gas generator including a casing having a lower water chamber and a pressure chamber therein above the water chamber, an inner cylinder within the casing and secured at its upper and lower ends thereto, having a lower flared and recessed portion and also having a lower cross support, a gas collecting cylinder opening downwardly within the water chamber and positioned within the said inner cylinder in spaced relation to the latter and upon said cross support, said casing also forming in its upper portion a gas storage chamber, an outlet valve at the upper portion of the collecting cylinder, opening into said gas storage chamber, and a carbide holding cylinder opening downwardly within the gas collecting cylinder and located therein and supported thereby for the purpose described.

60. 6. An acetylene gas generator including a casing having a fluid chamber, means forming a gas storage chamber open at its lower portion to the reception of fluid from said fluid chamber, a gas collecting device in the

gas chamber and opening downwardly into the fluid within the lower portion of said chamber, said device forming therein a collecting chamber having an upper valved gas outlet opening into said storage chamber, means forming a pressure chamber within the said casing on the surface of the fluid in the fluid chamber and opposing the pressure within the gas collecting device through the fluid of the fluid chamber and the lower portion of the gas chamber, and carbide holding means within the gas collecting device to and from which the level of fluid shifts under variations of pressure in said pressure chambers.

7. An acetylene gas generator including a casing having a fluid chamber, means forming a gas storage chamber open at its lower portion to the reception of fluid from said fluid chamber, a gas collecting device in the gas chamber and opening downwardly into the fluid within the lower portion of said chamber, said device forming therein a collecting chamber having an upper valved gas outlet opening into said storage chamber, means forming a pressure chamber within the said casing on the surface of the fluid in the fluid chamber and opposing the pressure within the gas collecting device through the fluid of the fluid chamber and the lower portion of the gas chamber, and carbide holding means within the gas collecting device to and from which the level of fluid shifts under variations of pressure in said pressure chambers, said carbide holding means being supported by the gas collecting device for removal with the latter from the casing in order to replenish the supply of carbide.

8. An acetylene gas generator including a casing having a fluid chamber, means forming a gas storage chamber open at its lower portion to the reception of fluid from said fluid chamber, a gas collecting device in the gas chamber and opening downwardly into the fluid within the lower portion of said chamber, said device forming therein a collecting chamber having an upper valved gas outlet opening into said storage chamber, means forming a pressure chamber within the said casing on the surface of the fluid in the fluid chamber and opposing the pressure within the gas collecting device through the fluid of the fluid chamber and the lower portion of the gas chamber, and carbide holding means within the gas collecting device to and from which the level of fluid shifts under variations of pressure in said pressure chambers, and a valve disposed externally of the casing for manual control, having communicating connections with the said gas storage chamber and the said pressure chamber.

JAMES H. BROWN.
